WINDOW RAISER

Walter D. Grab, Parkersburg, W. Va.

Application October 9, 1941, Serial No. 414,348

3 Claims. (Cl. 268—126)

This invention relates to window raisers for automotive vehicles and has for an object to provide a device of this character which may be operated with minimum manual effort to move the window pane to any desired adjusted position.

A further object is to provide a device of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming a part 20 of this specification:

Figure 1 is an elevation looking to the inside of a motor vehicle door equipped with a window raiser constructed in accordance with the invention.

Figure 2 is a longitudinal sectional view of the window raiser with parts in elevation.

Figure 3 is a detail sectional view taken on the line 3—3 of Figure 1.

Figure 4 is a view similar to Figure 3, but showing the dog depressed.

Figure 5 is a rear elevation of the window raiser shown in Figure 1.

Figure 6 is a detail plan view showing the position of the parts when the barrel is rotated in one direction.

Figure 7 is a detail plan view showing the parts when the barrel is rotated in the opposite direction.

Figure 8 is a detail perspective view of the hub and operating shaft.

Figure 9 is a detail perspective view of the barrel.

Referring now to the drawings in which like characters of reference designate similar parts in the various views, 10 designates a motor vehicle door and 11 the glass window pane thereof. For controlling the window pane, the window raiser forming the subject matter of this invention comprises a housing formed of two shells 12 and 13, which are secured together by bolts 14 to house the working parts, these bolts being engaged through the inner wall 15 of the door to secure the housing to the door. One of the bolts is also engaged through the short leg of 55

a U-shaped frame 16, the long leg of the frame being spaced from the housing and having riveted thereto, as shown at 17, the flattened intermediate portion of an elongated leaf spring 18 for counter-balancing the weight of the window pane, and which will be later described.

On operating shaft 19 is rotatably mounted in an axial tubular bearing 20 which is integral with the shell 13. The shaft is equipped with a crank handle 21 which may project through a slot 22 in the upholstery 23, if desired. As best shown in Figure 8, the shaft 19 has formed integral therewith a disk hub 24, and a split sleeve 25, comprising two companion arcuate sections 26, is formed integral with the hub. One of the sections is provided with a notch 27.

A cylindrical barrel 28 is received between the arcuate sections 26 and is provided at diametrically opposite points with longitudinal ribs 29 which are received in the spaces 30 between the arcuate sections. The barrel is provided with a collar 31 which is confined against a stop shoulder 32 formed in the shell 12. Beyond the collar the barrel is provided with a cylindrical extension 33 which fits in a tubular bearing 34 formed integral with the shell 12, and beyond the bearing, the extension is flattened, as shown at 35, to be received in an opening formed intermediate the ends of an operating lever 36. When the barrel is turned, the lever will be turned to raise or lower the window pane, as will presently be described.

A dog 37, best shown in Figures 3 and 4, is slidably mounted in a radial opening 38 formed in the barrel. A helical spring 39 is seated in the opening beneath the dog and tends constantly to hold the dog moved upward into engagement with ratchet teeth 40, formed on the inner periphery of the shell 12. The dog is provided with a bevelled end 41 and is cut away near the bevelled end to provide shoulders 42 which are also bevelled at the outer ends.

A helical spring 43 is sleeved on the shaft 19 and is secured at the ends in the shell 13 and in the disk hub 24. The spring normally holds the hub and extensions 26 in such position that the notch 27 is disposed laterally of the dog 37 so that the projecting portions 44 of the arcuate section on each side of the notch cannot engage over the shoulders 42 of the dog until the window is to be lowered.

The beforementioned leaf spring 18 is provided on each side of the lever 36 with a convolution 45 and the free ends of the spring are engaged in notches 46 in the lever on opposite sides of the

shaft 19. The upper end of the lever is provided with a pin 47 which engages in a longitudinal slot 48 formed in the lower frame member 49 of the window pane 11. The spring is under tension, so that when the parts are in normal position, and during operation of the device, the weight of the window pane 11 is approximately counter-balanced so that manual exertion in operating the device is reduced to a minimum.

When the window is closed, the dog 37 will be engaged back of a ratchet tooth 40, as shown in Figure 3. When the window is to be lowered, crank handle 21 is turned counter-clockwise, as best shown in Figure 4, and during the initial stages of rotation the projecting portions 44 of the arcuate sections will pass over the shoulders 42 on the dog 37 and depress the dog and finally lodge against the rib 29 in back of the dog so that continued rotation of the crank handle will turn the barrel 43, with resultant swinging of the upper end of the lever 36 downwardly to lower the window to any desired position, either partly open or fully open. When the crank handle is released, the spring 43 returns the hub 24 and arcuate sections 26 to normal position so that the dog is freed and is immediately moved by its controlling spring 39 to engage back of a tooth in the shell 12 and hold the window in adjusted open position.

When the window is to be raised, the crank handle is turned in a clockwise direction, as indicated in Figure 3, and in this position of the parts the rib 29 of the barrel by engaging the dog 37 rotates the barrel, the dog meanwhile moving over the ratchet teeth with ratchet action while the barrel is rotated to rock the lever 36 and raise the window to any desired position, either fully closed or partly closed. When the crank handle is released, the controlling spring 39 of the dog disposes the dog in back of one of the ratchet teeth to hold the window in adjusted closed position.

From the above description it is thought that the construction and operation of the invention will be fully understood without further explanation.

What is claimed is:

1. The combination with a motor vehicle window and door of a housing secured to the door, an operating shaft rotatably mounted in the housing, a disk hub formed integral with the shaft, a split sleeve integral with the hub comprising two companion arcuate sections, one of the sections being provided with a notch, a cylindrical barrel received between the sleeve sections provided at diametrically opposite points with longitudinal ribs received in the space between the arcuate sections, an operating lever connected to the barrel and to the window for raising or lowering the window when the barrel is turned axially, a spring pressed dog carried by the barrel, ratchet teeth formed on the inner periphery of the housing engaged by the dog, said dog having spaced shoulders, said notch being adapted to receive said dog and permit the

adjacent end of the companion sleeve section passing over the shoulders to depress the dog and subsequently engage against one of said ribs of the barrel to rotate the barrel for lowering the window, a spring for returning the dog to normal position after each actuation of the barrel, and a helical spring secured stationary intermediate its ends adjacent to the housing and having its opposite ends engaging the lever on opposite sides of the pivot of the lever to counter-balance the weight of the window pane.

2. The combination with a motor vehicle window and door of a housing secured to the door, an operating shaft rotatably mounted in the housing, a disk hub formed integral with the shaft, a split sleeve integral with the hub comprising two companion arcuate sections, a cylindrical barrel received between the sleeve sections provided at diametrically opposite points with longitudinal ribs received in the space between the arcuate sections, the ends of said sections engaging said ribs to turn the barrel in either direction when the shaft is turned in either direction, ratchet means between the barrel and the housing, means releasing the ratchet means when the shaft is turned in one direction and rendering the ratchet means operative when the shaft is turned in the opposite direction, a helical spring sleeved on the shaft and connected to the hub and to the housing to normally hold the arcuate sleeve sections out of operative engagement with the ribs of the barrel, a bracket secured to the housing, an extension on the barrel journaled in the bracket, a lever fixed intermediate its ends to said extension and connected to the window, and a leaf spring fixed to the bracket having the ends engaged in notches on opposite sides of the lever for counterbalancing the weight of the window.

3. The combination with a motor vehicle window and door of a housing secured to the door, an operating shaft rotatably mounted in the housing, a disk hub formed integral with the shaft, a split sleeve integral with the hub comprising two companion arcuate sections, a cylindrical barrel received between the sleeve sections provided at diametrically opposite points with longitudinal ribs received in the space between the arcuate sections, the ends of said sections engaging said ribs to turn the barrel in either direction when the shaft is turned in either direction, releasable ratchet means between the barrel and housing, a bracket secured to the housing, an extension on the barrel journaled in the bracket, a lever fixed intermediate its ends to the extension and having a pin and slot connection at one end with the window for operating the window when the barrel is turned, a leaf spring fixed to the bracket provided with spring convolutions disposed above and below the lever and terminating in curved ends engaged in notches on the upper and lower edges of the lever on opposite sides of the barrel to counter-balance the weight of the window.

WALTER D. GRAB.
